JOHN V. ABRONSKI, OF PITMAN, NEW JERSEY

WINDOW SCREEN

Application filed June 1, 1929. Serial No. 367,706.

The present invention relates to window screens and particularly to screens comprised of slidable sections.

An object of the invention is to provide an improved screen of this character.

A further object is to provide a window screen of sturdy construction which may be readily adjusted as to extent and as to position within the window opening.

10 A still further object is to provide a screen constructed of adjustable sections which will completely close the entire opening in a window to which the screen may be applied regardless of the adjustment of the sections to each other necessary to fill said opening.

15 A further object is to provide a screen construction which lends itself to the facilitous construction of its frames by metal extrusion processes.

20 A further object is to provide a screen frame composed of metal extruded, drawn, rolled, stamped or otherwise produced having an integral construction of all of the parts of each frame member and so shaped and constructed that a screen when attached thereto will at the same time be drawn tight.

25 A further object is to provide frames and screen bodies so connected therewith that when the sections are connected together for relative sliding that friction and fouling between the screen bodies will be reduced to a minimum without providing a gap between the relative sliding members.

30 A further object is to provide a screen frame constructed of members each formed of a single piece of metal extruded, drawn, rolled, stamped or otherwise produced so shaped or formed that the frame will be sturdy and rigid and at the same time will have no openings tubular or otherwise as used to obtain sturdiness and rigidity in former constructions.

35 The invention comprises inner and outer screen sections slidable relatively in overlapping relation and mounted for sliding as a whole in a direction at right angles to the relative slidable relationship.

40 The construction may provide for closing the gap ordinarily resulting from the overlapping of screen sections by forming

the outer section with a member extending to the inner surface of the inner section, as a flange at its upper end overlapping the upper edge of the inner member and by the provision of members on the lower rails of 55 both screen sections adapted to rest on the sill of the window casing.

The sturdiness of the screen organization may be improved and its manufacture facilitated by making the frames of metal extruded, drawn, rolled, stamped or otherwise produced and uniting the screen thereto by splines fitting in undercut grooves having openings of lesser width than the greatest width of the grooves, the splines taken with 60 65 the screen material being of greater width than the openings.

70 The sliding connection between the sections may be improved and strengthened by providing on one section oppositely disposed tongues slidable in similarly disposed grooves on the other section. Sliding connection between the window casing and the screen frames may be provided by forming the sides with lateral hooked ribs defining grooves constituting slideways and providing the window casing with hooked ribs constituting slides projecting therefrom and complementary in cross-section to the slideways.

75 For a better understanding of the invention, reference may be had to the accompanying drawings, in which:

Figure 1 shows the application of a form of my invention to a window casing;

Figure 2 is a section on the line 2—2 of 80 Figure 1, showing the screen and its associated slides in plan;

Figure 3 is a section on the line 3—3 of Figure 1, further showing the relation of the screen sections to each other and to the 85 slides;

Figure 4 is a detail view showing the frame of one of the screen sections, the same being represented on an enlarged scale compared with Figures 1, 2 and 3,

Figure 5 is a section on the line 5—5 of Figure 4, further illustrating the construction of this section,

Figure 6 is a further enlarged detail showing the connection of one of the screen frames 100

with the slide attached to the window frame and the manner of attaching the screen body to the frame members.

Figure 7 is a view similar to Figure 4, showing the frame of the other of the screen sections,

Figure 8 is a section on the line 8—8 of Figure 7, further illustrating the construction thereof,

Figure 9 is a sectional detail on an enlarged scale compared with Figures 7 and 8, showing the manner of connecting the wire cloth to the central frame members,

Figure 10 is a section on the line 10—10 of Figure 1, showing the sliding connection between the screen sections, the same being represented on an enlarged scale.

Figure 11 is a view similar to Figure 6, showing a somewhat different construction of the sliding connection between the slide and slideway, and a variation in the construction of the spline for holding the screen body to the frame, and

Figure 12 shows a reversal of the slide and slideway.

Referring to the drawings in detail by reference characters, 15 designates the side frame members and 16 the sill of a window frame in which is slidably mounted the usual window casing 17 and in which is also mounted the sections 18 and 19 of my improved screen. The section 18 may be considered the inner section inasmuch as it is represented as lying toward the inside of the house and against the lower rail 20 of the window sash. These sections are comprised of wire cloth 21 held within suitable frames 22 and 23 in a manner which will be herein-after set forth.

The frame 22 comprises a side member or rail 24, a central member or rail 25, a top member or rail 26 and a bottom member or rail 27. In a similar manner the frame 23 comprises a side member or rail 28, a central member or rail 29, a top member or rail 30 and a bottom member or rail 31.

The two screen frames are slidably connected one with the other for extensible adjustments in order to fill the openings of windows of various widths. The sliding connection between these sections is clearly represented in Figure 10 of the drawings in which the top and bottom members 26 and 27 of frame 22 are provided respectively, with projecting tongues 32 and 34, the latter also defining one surface of a groove 33.

The groove 33 is extended in an upward direction as is also the tongue 32 while tongue 34 is extended downward. This groove may be arranged at an angle to the vertical while the tongue 32 may be in a vertical direction, as shown.

The upper frame member 30 is provided with a projecting flange 36 which, as clearly shown, has its inner face or edge 37 in the

same plane as the inner face of the upper frame member 26 and this frame is provided with a groove 38 in which the tongue 32 is slidably mounted while the lower frame member 31 has a tongue 35 extending therefrom into groove 33.

By this construction it will appear that the frame of the outer section through the tongue 35 and the flange 36 grips the tongues 32 and 34 therebetween, forming an inseparable connection between the outer and inner screen frames except by sliding the sections in an endwise direction. This construction, therefore, adds to the sturdiness of the connection between the screen sections and in consequence to the life of the screen.

The provision of the flange 36 extending the entire width of the frame member or rail 26 effectively prevents the formation of a passageway at the top of the screen, regardless of the position of adjustment of the screen sections one upon the other. Similarly, the particular construction provided in the connection of one bottom rail with the other is proof against such passageway occurring at the bottom of the screen frame of each section resting flat throughout its length against the window sill.

The screen material is bound to the frame members by means of splines or anchors 39, as in Fig. 9, shown as a solid member and in Fig. 11 as 39^a as a hollow tube, which latter construction affords greater resilience to the splines in forcing the same through the neck-like openings or channel 41 leading to the groove 40. These splines may be of cylindrical shape and in connecting the screen to the frame are forced into the grooves 40 which are similarly shaped and have openings 41, referred to above, in one of the surfaces of the frames of the sections.

The opening 41 is of a slightly less width than the greatest width of the groove, as shown in the detail views of Figs. 6, 9, 11 and 12, the same being too slight for illustration in Figs. 3, 5, 8 and 10, while the splines are of a suitable diameter to pass through the opening 41 and are also of such diameter that the passage therethrough when the screen is lapped thereabout will be effected only by exerting pressure thereupon to this end, the splines, together with the screen material, may be of greater diameter than the width of the openings, the screen material and channel sides having sufficient yielding qualities to permit the passage under sufficient force.

These openings 41, as stated above, are preferably in the nature of channels between more or less parallel walls in the nature of necks leading to the grooves 40, as shown in Figures 6 and 11. It may be desired that the portions of the frame between the channels and the inside of the frame should meet the channel in an angle and it may also be

desirable that the screen should emerge from the enlarged portions of the grooves with a bend around a similar angular construction in order that the said angles may bite into the mesh, thereby forming a firmer grip between these parts. Such angles are shown at 50 and 51, Figures 6, 9, 11 and 12.

The splines will be held in the grooves after being forced thereinto by the expansion of the screen material due to the inherent resiliency thereof. These grooves, as clearly shown in Figures 4 and 7, are formed in all of the rails comprising the frame of the section.

Sliding connection between the screen as a whole and the window frame is provided by forming in the side members 24 and 28 grooves 42 constituting slideways which may be L-shaped hooks in cross-section, as shown in Figure 6, or of a gradually curved hook shape in cross-section, as shown at 42^a in Figure 11, into which are projected tongues 43 and 43^a respectively, integrally formed with the strips 44 attached to the side members of the window frame and conforming in cross-section to the cross-section of the grooves, the tongues constituting slides on which the screen frames move.

By this construction it will be readily seen that after the window screens have been adjusted to the width of the window and the slides placed in the slideways that the sections will be held against contraction one upon the other with a consequent dislodgment from the window and there is left no opening admitting the ingress of insects.

This construction also provides for the raising and lowering of the screen as a whole without the raising or lowering of the window sash and also permits of the raising or lowering of the sash independently of the screen, the screen being mounted outside or inside of the window sash, as the case may be, and having its top rails resting against the lower rail of the particular sash with which it is associated. It is to be understood that the screen frame may rest against the lower rail of the upper or lower sash, as may be desired or as convenience or taste may dictate.

Figure 12 shows the slide and slideways reversed from the showing in Figure 6, the slide 43^a being on the side frame of the screen and the slideway 42^a formed in the strips 44^a attached to the window frame.

It will appear, should the window frame be out of plumb due to settling of the building or for any other cause that in sliding the screen as a whole up and down, the sections will adjust themselves to such deformity of the window opening. A certain amount of play between the slides and slideways may be provided to this end. Such play is shown between the slides and slideways in Figures 6 and 11. Such play is in fact ordinarily

present between relatively sliding members. Such play between the relatively sliding sections is not shown but is always sufficiently present for purposes of this invention where one member is slidably connected with another.

The formation of the frame members may be facilitated by making them of extruded metal in a well known manner but they may also be drawn, rolled, stamped or otherwise produced and the slideways associated therewith may also be formed by either process. The frames having been formed, the screen may be laid flat thereupon overlapping the grooves, whereupon the splines may be placed opposite the openings of these grooves and forced thereinto with the screen material lapped around the circumference thereof.

It is to be understood that the foregoing description while setting forth only the specific embodiment herein shown is intended, with the drawings, to be illustrative of the invention and in no way to bind the applicant to any specific detail herein set forth and it is to be understood that the various details may be changed or modified within the scope of the invention hereinbefore set forth and hereinafter claimed.

I claim:

1. A window screen comprising panels adapted for horizontally slidable adjustment and means at the remote edges of said panels tending to prevent said adjustment.

2. A window screen comprising panels adapted for horizontally slidable adjustment and means at the remote edges of said panels tending to prevent said adjustment, said means providing for vertical organized movement.

3. An expansible window screen organization, and means at the remote vertical edges providing for vertical organized movement the while preventing area diminution.

4. A window screen embodying horizontally slidably adjustable units and connections at the remote edges of the units providing for vertical sliding movement and preventing movement in any other direction.

5. The combination with a window frame, a panel extending from one side of the frame but stopping short of the opposite side, and means connecting the panel with the first mentioned side maintaining the panel against lateral movement in any direction.

6. The combination with a window frame, a panel extending from one side of the frame but stopping short of the opposite side, and means connecting the panel with the first mentioned side maintaining the panel against lateral movement in any direction, the while providing for vertical sliding movement.

7. The combination with a window frame, a panel extending from one side of the frame but stopping short of the opposite side, and means connecting the panel with the first men-

tioned side maintaining the panel against lateral movement in any direction, the while providing for vertical sliding movement, a second like panel similarly connected opposite the first mentioned connection, and means connecting the two panels providing for horizontal relative movement, the while preventing relative vertical movement.

8. A window screen comprising frame members in slidable contact with registering grooves formed in the contacting surfaces, screen material having edges inserted one into each groove, locking means within the grooves, and means to maintain the members in sliding relation with the screen materials juxtaposed.

9. A window screen comprising frame members in slidable contact with registering grooves formed in the contacting surfaces, screen material having edges inserted one into each groove, locking means within the grooves, and means to maintain the members in sliding relation with the screen materials interposed and juxtaposed.

10. A window screen comprising frame members in slidable contact with registering grooves with constricted openings formed in the contacting surfaces, screen material having edges inserted one into each groove, locking means within the grooves of greater width than the constricted openings within the grooves, and means to maintain the members in sliding relation with the screen materials juxtaposed.

11. A window screen comprising frame members in slidable contact with registering grooves with constricted openings formed in the contacting surfaces, screen material having edges inserted one into each groove, locking means within the grooves of greater width than the constricted openings within the grooves, and means to maintain the members in sliding relation with the screen materials interposed and juxtaposed.

12. A window screen comprising frame members in slidable contact with registering grooves formed in the contacting surfaces, screen material having edges inserted one into each groove, locking means within the grooves and depressed wholly below the plane of the surface, and means to maintain the members in sliding relation with the screen materials juxtaposed.

13. A window screen comprising frame members in slidable contact with registering grooves formed in the contacting surfaces, screen material having edges inserted one into each groove, locking means within the grooves and depressed wholly below the plane of the surface, and means to maintain the members in sliding relation with the screen materials interposed and juxtaposed.

14. A window screen comprising frame members in slidable contact with registering grooves formed in the contacting surfaces,

screen material having edges inserted one into each groove, splines within the grooves, and means to maintain the members in sliding relation with the screen materials juxtaposed.

15. A window screen comprising frame members in slidable contact with registering grooves formed in the contacting surfaces, screen material having edges inserted one into each groove, splines within the grooves, and means to maintain the members in sliding relation with the screen materials interposed and juxtaposed.

16. A window screen comprising frame members in slidable contact with registering grooves with constricted openings formed in the contacting surfaces, screen material having edges inserted one into each groove, splines within the grooves and depressed wholly below the plane of the surface, and means to maintain the members in sliding relation with the screen materials juxtaposed.

17. A window screen comprising frame members in slidable contact with registering grooves with constricted openings formed in the contacting surfaces, screen material having edges inserted one into each groove, splines within the grooves and depressed wholly below the plane of the surface and means to maintain the members in sliding relation with the screen materials interposed and juxtaposed.

18. A window screen comprising frame members in slidable contact with registering grooves with constricted openings formed in the contacting surfaces, screen material having edges inserted one into each groove, splines of greater width than the constricted openings within the grooves and depressed wholly below the plane of the surface, and means to maintain the members in longitudinal sliding relation with the screen materials juxtaposed.

19. A window screen comprising frame members in slidable contact with registering grooves with constricted openings formed in the contacting surfaces, screen material having edges inserted one into each groove, splines of greater width than the constricted openings within the grooves and depressed wholly below the plane of the surface, and means to maintain the members in longitudinal sliding relation with the screen materials interposed and juxtaposed.

20. A window screen unit having a plane face, and a second unit upon the side opposite said plane face, said second unit having a flange extending over said first unit and forming a channeled slideway, the remote margin being a plane surface in planar unity with the face of the first unit.

21. A window screen unit having a plane face, and a second unit upon the side opposite said plane face, said second unit having a flange extending over said first unit and forming a curvilinear channeled slideway,

the remote margin being a plane surface in planar unity with the face of the first unit.

22. A window screen unit having a plane face, and a second unit upon the side opposite said plane face, said second unit having a flange extending over said first unit and forming a channeled slideway embracing an edge of the first unit the remote margin being a plane surface in planar unity with the face of the first unit.

10 23. A window screen unit having a plane face, and a second unit upon the side opposite said plane face, said second unit having a flange extending over said first unit and forming a curvilinear channeled slideway embracing an edge of the first unit the remote margin being a plane surface in planar unity with the face of the first unit.

15 In testimony whereof I have signed my name to this specification.

JOHN V. ABRONSKI.
